UNITED STATES PATENT OFFICE.

IRVIN RADER, OF READING, PENNSYLVANIA, ASSIGNEE TO THE NOLDE AND HORST COMPANY, OF READING, PENNSYLVANIA, A CORPORATION OF PENNSYLVANIA.

EMBROIDERY-FRAME HOLDER FOR SEWING MACHINES.

Application filed April 21, 1923, Serial No. 633,593. Renewed September 25, 1925.

To all whom it may concern:

Be it known that I, IRVIN RADER, a citizen of the United States, residing at Reading, in the county of Berks and State of Pennsylvania, have invented certain new and useful Improvements in Embroidery-Frame Holders for Sewing Machines, of which the following is a specification.

My invention relates to sewing machines, and particularly to work-holder or tambour frame attachments therefor, and comprises means for positioning and securing the coacting holder members to facilitate the placing and securing of the work therein for subsequent sewing or embroidering operation. The invention is fully described in connection with the accompanying drawing, and the novel features pointed out in the claims.

Fig. 1 indicates in side elevation parts of a sewing machine with the coacting members of a work holder shown partly in section, and held in separated position for introduction of the work; a side plate of the table being removed to more clearly disclose the operation of the clamping devices pivotally mounted therein.

Fig. 2 is a partial plan view of the work table with one member of the work holder held in position thereon.

Fig. 3 is a cross section of the work table substantially on the line 3—3 of Fig. 1.

In the drawings 5 represents the needle-bar head and 6 the work table of an ordinary sewing machine adapted for embroidering, the table shown being of known cylindrical form for operating on tubular material such as seamless knitted stockings, for which my improvements are particularly applicable; it being understood however, that with slight changes, my improvements may be equally applicable to the usual flat work table.

The work holder or tambour frame, as shown, comprises two separable coacting ring members 8 and 9, member 8 fitting within the vertical wall of member 9 and seating against an inwardly extending bottom flange 10 of the latter, which flange preferably projects inward beyond said ring member 8 for engagement of clamping devices as hereinafter described; and member 8 is provided as shown, with outwardly flaring upright extensions 12, 12, which form

handles for conveniently lifting it into and 55 out of engagement with member 9.

In operating on seamless stockings, the tubular fabric is drawn over the cylindrical work table 6, and holder member 9 inserted in such placed tube and both adjusted 60 until the stocking part to be operated upon is embraced within the open central portion of the holder and the latter positioned under the needle, after which the ring member 8 is forced to position to clampingly hold the 65 properly stretched fabric between the vertical walls of said coacting ring members and also between the lower edge of member 8 and top face of inwardly extending flange 10 of member 9. 70

To facilitate this insertion and placing of the holder within the stocking, I provide the work table 6 with clamping devices 15, 15, and 16, 16, as shown, adapted to engage with flange extension 10 of ring member 9, so that the stocking may be readily pushed over said united ring member and table and adjusted to position; and I also provide the needle bar head 5 with spring suspension 75 fingers 17, 17 adapted to hold thereon ring member 8 in raised position above clamped ring member 9 during such positioning of the stocking. 80

The clamping devices 15, 15 and 16, 16 are preferably arranged on opposite sides of 85 table 6 and each pivotally secured thereto by a screw bolt 20 engaging in the straight side wall portions 21, 21 formed by the flattened forward top face 22 of said table, as shown; the pair 15 and 16 on each side being 90 arranged to reversely swing on their pivots 20 so that their hooked clamping ends 23, 23 will lie below said table face 22 or rise above the latter to engage with flange 10 of ring member 9. 95

The actuating means for each pair of clamping devices 15 and 16 is provided as shown, by plates 25, 25 having slots 26, 27 engaging the pivot bolts 20, 20 and slidably mounted thereon between the side walls 21, 21 and their respective pair of devices, 15 and 16; each plate 25 also having vertical slots 28 and 29, slot 28 engaging a stud 30 on its respective device 15 above pivot 20, and slot 29 engaging a similar stud 31 on its 100 respective device 16 below pivot 20, so that movements of said slides will reversely swing each pair of devices 15 and 16 into 105

raised or lowered position with relation to table face 22. The forward ends of plates 25, 25 project beyond table 6 and have an integral connecting member 32 as shown 5 forming a handle for their joint manipulation; and I preferably provide one or both slide plates 25, 25 with a spring pressed 10 detent 33, as shown, movably carried with the latter end yielding passing under fixed post 35 projecting through slide slot 36, to bear against opposite sides of said post and retain said slides against unintentional displacement at opposite extremes of their movement. Rounded cover plates 37, 37 are 15 preferably provided for said slide plates 25, 25 and their respective pairs of clamping devices 15, 16, 15, 16 and the heads of pivot screw bolts 20, 20, 20, 20 are sunk thereon as 20 shown to present a smooth finished surface that will not catch or tear the fabric loops as the stocking is drawn over the table and work member 9 held thereon.

In operation, work holder member 8 is sprung over suspension fingers 17, 17 to hold 25 it in raised position, and member 9 placed on table and slide handle 32 pulled out, which movement, as described, raises the hooked end 23 of each pair of clamping devices 15, 16, 15, 16 above the table top 22, 30 to engage with extended flange 10 of said member 9, positioning the same with respect to the needle and securely holding it in position for readily pushing the stocking over it and the work table. When the stocking 35 is properly adjusted, ring member 8 is lowered and engaged with member 9 to clamp the fabric, and handle 32 pushed in to free the holder for required movement under the needle during the embroidering operation; 40 after which the holder with the fabric still held thereon is again secured to the table by pulling out handle 32; ring member 8 lifted out and hung on suspension fingers 17, 17 when the loosed stocking may be drawn off 45 the table 6 and member 9 leaving the holder members positioned for the next stocking.

Obviously my improvements are adapted for flat fabrics as well as tubular, and for any operation requiring a work holder or 50 tambour frame, the temporarily fixed positioning of the separated coacting members thereof on the machine greatly facilitating the placing and securing of the fabric. Also

modifications adapting it to various types of machines may be readily made and I do 55 not desire to limit myself to the specific construction shown and described.

What I claim is:

1. The combination with a sewing machine having a work table and an overhanging needle-bar head, of a work holder comprising a ring member having an inwardly extending circular flange adapted to seat upon the work table and a work-clamping ring member insertable in said flanged ring member, and means for clamping the latter to the work table comprising clamping devices pivotally secured to the work table and actuating means for swinging said devices into and out of engagement with said inwardly extended circular flange. 70

2. The combination with a sewing machine having a work table and an overhanging needle-bar head, of a work holder comprising a ring member having an inwardly extending circular flange adapted to seat upon the work table and a work-clamping ring member insertable in said flanged ring member, and means for clamping the latter to the work table comprising clamping devices pivotally secured to the work table and actuating means for swinging said devices into and out of engagement with said inwardly extended circular flange; said needle bar head being provided with means for holding said insertable needle-clamping member in inoperative position. 75

3. The combination with a sewing machine having a work table and an overhanging needle bar head, of a work holder comprising a ring member having an inwardly extending circular flange adapted to seat upon the work table and a work-clamping ring member insertable in said flanged ring member, and means for clamping the latter to the work table comprising clamping devices pivotally secured to the work table and an actuating plate therefor slidably mounted upon the work table and engaging said pivoted devices so as to swing the latter into 100 or out of engagement with said inwardly extended circular flange. 90

In testimony whereof I affix my signature.

IRVIN RADER.
